UNITED STATES PATENT OFFICE.

CALVIN B. PATCH, OF GLENELLYN, ILLINOIS, ASSIGNOR TO WILLIAM H. MINER, OF CHAZY, NEW YORK.

YOKE.

1,242,852.

Specification of Letters Patent.

Patented Oct. 9, 1917.

Application filed July 19, 1916, Serial No. 110,009. Renewed August 27, 1917. Serial No. 188,492.

To all whom it may concern:

Be it known that I, CALVIN B. PATCH, a citizen of the United States, residing at Glenellyn, in the county of DuPage and State of Illinois, have invented a certain new and useful Improvement in Yokes, of which the following is a full, clear, concise, and exact description, reference being had to the accompanying drawings, forming a part of this specification.

This invention relates to improvements in yokes.

An object of the invention is to provide a yoke having a detachable connection with a draw bar and wherein is employed a removable locking block having simple means associated therewith for retaining the block in operative position.

In the drawing forming a part of this specification, Figure 1 is a part side elevation, part longitudinal section of a draw bar and yoke illustrating my improvements in connection therewith. Fig. 2 is a horizontal, sectional view of the structure illustrated in Fig. 1 and taken on the broken line 2—2 thereof. Fig. 3 is a front end elevation of the improved yoke. Fig. 4 is a transverse, vertical section taken on the line 4—4 of Fig. 1. And Fig. 5 is a perspective of the locking block.

In said drawing, the improved yoke is designated generally by the reference A and 10 denotes the draw bar, the latter having the usual upper and lower shoulders 11 and 12. The yoke A, as shown, comprises an upper arm 13, lower arm 14, rear connecting piece 15, and a hooded forward end, the latter comprising side walls 16—16, top wall 17, and downwardly offset bottom wall 18, the latter merging into the lower arm 14, as clearly illustrated in Fig. 1. The top wall 17 is provided on its inner side with a transverse shoulder or gib 19 which engages the upper shoulder 11 of the draw bar. The side walls 16—16 are provided with angular shaped slots 20 through which may be inserted transversely, a locking block B. The locking block B is of substantially angular cross-section and has an upstanding flange 21 which cooperates with the lower shoulder 12 of the draw bar, and a horizontal flange 22. The side walls of the hood are preferably provided with reinforcements or shoulders 23 on their inner faces to form a better

backing for the locking block when the latter is under strain during draft movements.

To retain the locking block B in position, the bottom wall 18 of the hood is provided with a slot having an enlarged rectangular portion 24 and a narrow communicating portion 25. The enlarged portion 24 of the slot is adapted to have inserted vertically therethrough the head 26 of a short bolt. The under-face of the block B is provided with a properly located slot 27 to accommodate the head 26 of the bolt so that the latter, after it has been inserted through the rectangular opening 24, may be slipped forwardly to the position most clearly indicated in Fig. 1. The inner face of the bottom wall 18 is counter-sunk as indicated at 28 to receive the head of the bolt when in the position shown in Fig. 1. And small shoulders 29 are provided, which prevent the head of the bolt from slipping rearwardly after it has been seated in the counter-sink 28. The bolt is held in position by the nut 30 and cotter 31.

As will be apparent from an inspection of Figs. 1 and 4, the counter-sink 28 is relatively shallow so that a portion of the bolt head will extend up above the top surface of the lower wall 18 and hence be located partly within the slot 27 formed in the under-face of the block B. By this means, the block B is prevented from lateral movement as will be apparent.

In the preceding description, it will be seen that the expedient which I have provided for retaining the block B in position, is simple and inexpensive and the bolt may be inserted and removed with ease. In addition to the foregoing, it is unnecessary to extend the block B beyond the side walls of the hood, thus providing for those conditions in railway service where the space between the front stops is comparatively narrow. Furthermore, by making the openings 20 in the side walls somewhat larger than the section of the block B, it is apparent that, by first removing the bolt, the block B may be shifted laterally sufficiently to clear one side of the hood, and then twisted and withdrawn from the forward end of the hood. After this has been done, it is apparent that the draw bar may be dropped down and removed from the yoke without disturbing the latter or the gear therewithin.

I claim:

1. A yoke for draft riggings having a hooded forward end within which is adapted to be received a shouldered draw bar butt, a removable shouldered locking block associated with said hood and adapted to engage a shoulder of the draw bar butt, the bottom wall of the hood having an opening therein, and a short bolt having its head insertible through said opening and adapted to engage said locking block to prevent the latter from being displaced.
  2. A yoke for draft riggings formed at its forward end to receive a draw bar butt therewithin, a removable locking block adapted to engage a shoulder on the draw bar, one wall of said end of the yoke having a slot therein, one portion of the slot being enlarged to permit the insertion of a bolt head therethrough, the locking block being provided with a slot arranged to aline with said bolt slot, and a bolt insertible through the slot therefor and having a portion of its head located within the slot in the block, when the bolt is in operative position.
  3. A yoke for draft riggings having a hooded forward end within which is adapted to be received a draw bar butt, the bot-
- tom wall of said hooded end being provided with a T-shaped slot, a shouldered locking block insertible laterally through slots in the side walls of the hooded end, and means insertible through said T-shaped slot in the hooded end and adapted, when in operative position, to engage the under-face of said locking block and prevent shifting thereof.
4. A yoke for draft riggings having a hollow hood at its front end, the top wall of said hood being provided with a shoulder to engage the upper shoulder of a draw bar butt, a shouldered locking block insertible through the side walls of said hood and arranged to engage the lower shoulder of a draw bar butt and a short bolt insertible through the bottom wall of said hood, the head of said bolt, when the latter is in operative position, being located within a slot on the underface of the block.

In witness that I claim the foregoing I have hereunto subscribed my name this 15th day of July, 1916.

CALVIN B. PATCH.
